UNITED STATES PATENT OFFICE

149,045

DESIGN FOR A KITCHEN RANGE

Carl G. Björnerantz, Evanston, Ill., assignor to
 Sears, Roebuck and Co., Chicago, Ill., a corpora-
 tion of New York

Application June 21, 1946, Serial No. 130,921

Term of patent 7 years

(Cl. D81—4)

To all whom it may concern:

Be it known that I, Carl G. Björnerantz, a citizen of the United States and a resident of Evanston, in the county of Cook and State of Illinois, have invented a new, original, and ornamental Design for a Kitchen Range, of which the following is a specification, reference being had to the accompanying drawing, forming a part thereof.

Fig. 1 is a front elevation of a kitchen range, embodying my new design.

Fig. 2 is a side elevation of the range illustrated in Fig. 1; and

Fig. 3 is a top plan view thereof, the dominant features of the design residing in the proportions shown in full lines.

The other side of the range is similar to and symmetrically opposite the showing in Fig. 2.

I claim:

The ornamental design for a kitchen range, substantially as shown and described.

CARL G. BJÖRNCRANTZ.
